[73] Assignee: McGraw-Edison Company, Rolling
Meadows, Ill.

[57] CLAIM

[**] Term: 14 Years

The ornamental design for accessory solution tank for
vacuum cleaner, as shown and described.

[21] Appl. No.: 218,041

DESCRIPTION

[22] Filed: Dec. 18, 1980

FIG. 1 is a top plan view of an accessory solution tank
for a vacuum cleaner showing my new design;
FIG. 2 is a bottom plan view thereof;
FIG. 3 is a right side elevational view thereof;
FIG. 4 is a left side elevational view thereof;
FIG. 5 is a rear elevational view thereof;
FIG. 6 is a front elevational view thereof; and
FIG. 7 is a perspective view thereof.

[51] Int. Cl. ..... D15—05

The broken line representation of a wet/dry vacuum
cleaner in FIG. 7 is for purposes of illustration only and
forms no part of the claimed design.
